SELECTIVE AUTOMATIC PHONOGRAPH

Russell I. Wilcox, Chicago, Ill., assignor of one-half to Justus P. Seeburg, Chicago, Ill.

Application July 3, 1933, Serial No. 678,753

13 Claims. (Cl. 274—10)

This invention relates to a selective automatic phonograph adapted to play a selected one of a series of records or to play the records one after another, if desired.

5 The improved phonograph is intended to be enclosed within a cabinet and to be controlled from the outside by means of coin freed mechanism.

10 The invention will fully be understood from the following description of a preferred embodiment thereof taken in conjunction with the accompanying drawings, in which

15 Figure 1 is an elevational sectional view through the upper part of the cabinet showing the mechanism in elevation, the section being taken at a point near the front wall of the cabinet;

Fig. 2 is a sectional plan taken on the line 2—2 of Fig. 1;

20 Fig. 3 is a sectional plan taken on the line 3—3 of Fig. 1;

Fig. 4 is a sectional elevation taken on the line 4—4 of Fig. 1, the turntables and records being omitted, together with their spindle and associated parts;

25 Fig. 5 is a vertical sectional detail view taken on the line 5—5 of Fig. 1, illustrating more particularly the record selecting mechanism;

Fig. 6 is a vertical sectional detail view taken 30 on the line 6—6 of Fig. 2; and

Fig. 7 is a sectional detail view taken on the line 7—7 of Fig. 3.

35 Referring to the drawings, the cabinet is designated by the reference numeral 10, this cabinet being preferably tall so as to bring the operating portions to a suitable height for easy manipulation by patrons. At an intermediate height the cabinet is provided with a transverse partition 11, which is the bottom of an upper compartment 12 provided with one or more windows 13 through 40 which various parts of the operating mechanism can be observed.

45 The mechanical parts of the mechanism are supported in a frame 14, which, in turn, is secured to the horizontal partition 11 preferably by means of bolts. The partition 11 is preferably made removable so that the phonographic apparatus can very readily be mounted in the cabinet and very readily removed therefrom when desired. The frame 14 suitably comprises a pair of end members 15 rigidly connected by bars 16. The frame 14 also comprises a pair of vertical posts 17 rigidly secured to the rear bars 16 and secured to each other by bridge members 18 and 50 19 at their upper ends and near their lower ends,

respectively. One of the end frame members 15 has rigidly secured thereto a double arm bracket 20 which provides spaced bearings for the record spindle 21, which projects upwardly almost to the level of the upper ends of the posts 17.

5 The upper end of the spindle 21 is provided with a bearing at the end of an arm 22, which is pivotally mounted on one of the posts 17, as shown in Fig. 1, by means of a pair of perforated lugs 23 through the openings of which the 10 post 17 passes. Between the lugs 23 there is rigidly mounted on the post 17 an abutment member 24.

15 A coil spring 25 is arranged between the abutment member 24 and the lower lug 23 so as to tend to move the arm 22 downwardly with its upper lug 23 bearing against the abutment member 24. In order accurately to position the arm 22 in cooperative relation with the spindle 21 I provide on the abutment member 24 a stop 26 20 which engages the arm 22 at the right position. I also provide on the abutment member 24 an upwardly projecting pin 27 which is adapted to enter into an opening in the arm 22 as said arm moves downwardly into cooperative position with 25 the spindle 21. The operation of the arm 22 will readily be understood. When it is desired to remove this arm from the upper end of the spindle 21 it is merely raised upwardly and moved in a clockwise direction, as viewed in Fig. 2, so as 30 to clear the records and their turntables and permit the same to be withdrawn from the spindle 21 and return thereto as desired.

35 As will readily be seen from Fig. 1, the spindle 21 projects upwardly through an opening in the partition 11. Immediately above this partition it has rigidly secured thereto a turntable 28 which is provided with an enlarged boss 29 through which the spindle 21 passes. The boss 29 may be supported on a collar 30 rigidly secured to the 40 spindle 21 and may also be rigidly secured to the spindle 21 by means of a screw 31. In equipping the machine with records to be played, a record 32 is applied to the spindle 21 so as to bring it in position upon the turntable 28. Thereafter a turntable 33 provided on its underside with a large boss 34 is applied upon the spindle 21 so that the lower face of the boss 34 rests upon the record 32. The turntable 33 and its boss 34 are preferably exactly the same as the 50 turntable 28 and its boss 29, differing only therefrom in that it is not rigidly secured to the spindle 21, but merely rests upon the record 32 therebelow.

55 The loading operation is continued by applying

ing records 35 and turntables 36 alternately upon the spindle 21 until the machine is fully loaded. In the specific embodiment shown the machine takes ten records, but obviously it may be adapted 5 to operation with any desired number of records. When the machine is fully loaded the arm 22 is returned to position so as to provide a top bearing for the spindle 21. The spindle 21 is provided with a driving pinion 37 which is driven 10 by a worm 38. The worm 38 is mounted on a shaft 39 which is provided with bearings in the bracket 20. The shaft 39 is connected to the spindle of an electric motor 40, mounted in a suitable manner upon the cabinet 10 with its 15 spindle in alignment with the shaft 39.

The shaft 21 is provided with a worm 41 which meshes with the pinion 42 freely mounted on a shaft 43 which is provided with bearings in the end frame members 15. The shaft 43 is the 20 main cam shaft and is provided with a player arm translating cam 44, a player arm tilting cam 45, a player arm carriage elevating cam 46 and a selector locking cam 47. These cams are rigidly mounted upon the shaft 43 so as to 25 operate associated mechanisms in proper sequence, which sequence will hereinafter be fully described.

The main cam shaft 43 also carries a rigid arm 48 which is adapted to cooperate with a timing switch or a counting timer switch to stop the 30 operation of the machine after one or a certain plurality of records, depending upon the number of coins inserted in the switch, have been played. The shaft 43 has also rigidly mounted 35 thereon an arm 49 which is adapted to actuate the record selector so that when the machine is set to play a plurality of records in succession, it will automatically shift from one record to another.

40 The pinion 42 and the shaft 43 are provided with complementary clutch elements so that the shaft 43 may at times be operatively connected to the pinion 42 and driven through said pinion from the motor 40. These clutch elements may 45 suitably comprise a disk 50 rigidly mounted on one side of the pinion 42, which disk is provided with a circumferential series of openings into which a pin 51 is adapted to enter. The pin 51 is carried by a collar 52 slidably but non-rotatably mounted on the shaft 43. The pin 51 is 50 normally pressed toward the disk 50 by means of a coil spring 53 which abuts against one face of the cam 44 and against a face of the collar 52. In order to prevent collar 52 from rotating 55 relatively to shaft 43 I preferably project the pin 51 between the furcations 54 of an element 55 pinned or otherwise rigidly mounted on the shaft 43. The clutching elements are controlled by lever 56, the forward end of which normally rests 60 on the cylindrical surface of the collar 52. Upon this surface is applied a cam 57 having an edge surface 58 inclined to the longitudinal axis of the shaft 43.

65 During the rotation of the shaft 43, which occurs in the clockwise direction as viewed in Fig. 4, the inclined surface 58 makes contact with the end of the lever 56, and this lever being held against movement to the left as viewed in Fig. 1, the collar 52 is forced to the right as 70 viewed in this figure until the pin 51 is withdrawn from the opening in the disk 50 in which it had been entered. When this pin is withdrawn the operative connection between the pinion 42 and shaft 43 is interrupted. The shaft 43 is 75 provided with a friction brake 59 so that it stops

promptly upon the withdrawal of the pin 51. The pinion 42 and shaft 43 remain unclutched until the forward end of the lever 56 is elevated so that said end rises above the inclined edge surface 58, which elevation is effected in a manner herein- 5 after described.

The player arm 60 is relatively flat and is of substantial weight at its free end. The purpose of making it flat is to enable it more readily to move between the records and minimize the 10 amount of vertical space required for a super-posed series of records. As best seen in Fig. 2 the player arm 60 comprises two similar forwardly projecting parts in spaced relation, the forward ends of which are connected by a bridge 15 61, which also serves as a bearing for a rod 62. The rod 62 is provided at its forward end, beyond the bridge 61, with means for receiving and se- 20 curing a needle 63. The rear end of the rod 62 extends operatively into a pick up member 64, 25 which may be of conventional type, but which is mounted upon the pick up arm 60 at a position remote from the needle. The player arm 60 is provided with rearwardly directed parallel arms which are pivotally mounted at their rear ends 30 upon a swinging carriage 65, best shown in Fig. 6. This carriage comprises forwardly projecting lugs 66 and 67 which are provided with openings in vertical alignment, through which passes a vertical guide rod 68. Vertical guide rod 68 is con- 35 nected rigidly by upper and lower elements 69 and 70 respectively, to a vertical rod 71 so as to provide a swinging frame with which the player arm 60 and the carriage 65 are adapted to swing in unison in a horizontal direction. The swing- 40 ing carriage 65 and likewise an associated car- 45 riage 72 are adapted to slide vertically upon the guide rod 68. The carriage 72 is essentially rec- 50 tangular in outline, the upper and lower members being provided with openings 72a through which 55 the guide rod 68 extends so as to enable the car- 60 riage to ride up and down thereon. The carriage 72 is provided with a forked extension 73 which 65 engages one of the posts 71 and keeps the carriage 72 from oscillation in a horizontal direction. 70

The lower lug 67 of the swinging carriage 65 rests upon the lower transverse member of the carriage 72, as clearly shown in Figs. 4 and 6. A screw 74 passing through a wall of the carriage 72 projects above the lug 67 and prevents verti- 75 cal separation of the carriages 65 and 72, keeping them together notwithstanding the free swinging 80 movements of the carriage 65 in the horizontal direction.

The carriage 72 is connected by a downwardly 85 extending link 75 to a lever 76 which will herein- 90 after be more fully described. The carriage 72 has pivotally mounted thereon a spring pressed dog 77 which is upwardly directed and adapted to engage with a pin of a selector mechanism, 95 hereinafter to be described. The upper end of the dog is sloped towards the right, as seen in Fig. 1, so that in the event that it comes in contact with one of said pins in the downward move- 100 ment of the carriage 72, the dog will pass said pin 105 freely.

The swinging carriage 65 comprises a rearwardly extending portion 78 provided with furcations at its rear end, which are located one on each side of the rod 71 so as to cause the player arm 60 70 and the swinging carriage 65 which carries it to swing in unison with the frame constituted by the guide rod 68, upper and lower elements 69 and 70 and rod 71. The rearwardly extension 78 has pivotally mounted thereon a horse shoe element 75

79 which is provided at its upper end with a pin 80 directed rearwardly towards the center of the rod 71. The rod 71 is provided with a longitudinal series of forwardly directed holes 81 adapted 5 to receive the pin 80 and hold the player arm in cooperative relation with any one of the records mounted on the spindle 21 in the manner hereinbefore described.

The horse shoe element 79 has a downwardly projecting leg 82 which carries a screw 83 adapted 10 to engage an abutment 84 on a carriage 72. The leg 82 is connected by means of a spring 85 to the swinging carriage 65, for example, to the pivot which secures the player arm 60 to this carriage.

15 This spring normally tends to keep the pin 80 in one of the openings 81. When, however, the player arm 60 is deflected into non-operating position, as shown in Fig. 2, the screw 83 engages the abutment 84, causing the horse shoe element

20 79 to swing about its pivots and withdraw the pin 80 from the openings in the rod 71. When this occurs in the operation of the device, as will hereinafter be more fully described, the player arm 60 and carriages 65 and 72 fall under their own 25 weight, which fall is damped in the manner hereinafter described.

The carriage 65 has pivoted thereto a plate 86 which extends upwardly behind the guide rod 68. This plate is provided with a roller 87 which rides 30 upon the rear face of the rod 68 during the upward and downward movements of the carriages and player arm. The weight of the player arm is counterbalanced to a suitable extent by springs 88 connected to said player arm and to the upper 35 end of the plate 86, the tension of these springs tending to hold the roller 87 in contact with the rod 68.

The player arm 60 is provided with a pair of downwardly projecting elements 89 between which 40 is mounted a roller 90 normally located some distance in front of the rod 68. This roller bears against the forward face of a rod 91 connected to the guide rod 68 by equal parallel links 92 adjacent its upper and lower ends. The links 92 are 45 freely pivoted to the rods 91 and 68 so that the rod 91 may be elevated in the manner hereinafter described. The links 92 are normally directed forwardly and downwardly from the rod 68 to the rod 91, so that the elevation of the rod 91 is 50 accompanied by a slight forward movement of said rod. The resulting forward movement of the roller 90 raises the player arm slightly and takes the needle out of contact with the record. The rod 91 is provided with a roller 93 which is adapted 55 to be engaged in the manner hereinafter described to elevate the rod 91.

Adjacent its lower end the guide rod 68 has rigidly mounted thereon a rod 94 which projects rearwardly and towards the left in normal operative position, as viewed in Fig. 3. At its free end the rod 94 has mounted thereon a roller 95 and also has pivotally mounted thereon a tooth 96, the function whereof will hereinafter be described. The lower element 70 of the swinging frame extends forwardly and is provided at its forward end with the helical cam 97 which extends downwardly in the clockwise direction, as viewed in Fig. 3. Below the lower element 70 a bar 98 is pivotally mounted on the guide rod 68. 60 This bar 98 is connected through a spring 99 to one of the posts 17 so that it tends to move in a clockwise direction when viewed in plan as in Fig. 3.

A screw 100, which extends through the said 75 post 17, serves as an abutment for the bar 98

limiting its tendency to move in this direction. The bar 98 carries an upstanding pin 101 on the right hand side of the forward extension of the element 70 so as to serve as an abutment therefor. The pin 101 permits independent movement of the player arm and its swinging arm to the left of the pin 101, but causes the bar 98 to move to the right away from the abutment 100 when the player arm and its frame move to the right beyond a predetermined position. This predetermined position is that at which the point of the needle is immediately above the beginning of the recording spiral of the record. When the player arm moves to the right beyond that position, which occurs during the normal operation of the machine, as will hereinafter be described, the lower element 70 engages the pin 101 and tensions the spring 99, which is thereby energized so as to return the player arm to initial playing position in the subsequent cycle of operation. During the return movement, that is the movement of the player arm to the left towards the record, it is desirable to lock the swinging frame to the bar 98, to prevent the inertia of the swinging frame and the parts carried thereon, including the player 15 arm, from swinging the needle into a position over the record considerably inside the initial playing position. For this purpose a latch 102 is mounted on the forward end of the bar 98 and is biased upwardly by a spring 103 so that it tends 20 to engage the forward extension of the swinging frame member 70 when it is brought into contact with the pin 101.

Under certain circumstances which will hereinafter be described, the tension in the spring 35 103 is released, this release preferably occurring after the inwardly moving player arm has become arrested in its initial playing position and during the downward tilting of the player arm resulting from the descent of the rod 91, the actuation of which will be more fully described. After the latch is released in this manner, the player arm and its swinging frame are free to move inwardly as a result of the engagement of the needle with the recording spiral of the record, 40 45 while the bar 98 is held against similar movement by the abutment screw 100.

A shaft 104 is supported between one of the end frame members 15 and an angular bracket 105, which is rigidly secured to two of the frame 50 bars 16, as shown in Fig. 4. The shaft 104 serves as a support for the lever 56, the lever 106 and lever 107. The lever 56 is provided with an arched extension 108 so that it is provided with two bearing collars through which the shaft 104 55 passes. A spring 109 engages a collar 110, rigidly and adjustably secured to the shaft 104, and the left hand collar of the lever 56, so that it tends to move this lever towards the left, as viewed in Fig. 3. The collar 110 serves as an 60 abutment, taking the thrust applied to the lever 56 during its engagement with the cam 57, previously described. The lever 56 extends rearwardly for a substantial distance beyond the shaft 104 and its rear end is of arcuate formation, having 65 its center approximately on the axis of the guide rod 68, the radius being such that the arcuate portion is located below the roller 95 and pivoted tooth 96, as best seen in Fig. 3. The extreme end portion of the lever 56 has secured 70 thereto a strip 111, the upper edge of which is serrated and adapted to be engaged by the pivoted tooth 96.

As seen in Fig. 3, the tooth 96 is adapted to extend forwardly of the strip 111 during the cycle 75

of operation. When the record begins to play the arm 94 moves in the clockwise direction, as viewed in Fig. 3, and the tooth 96 comes into engagement with the serrated upper edge of the strip 111, the tooth 96 being directed forwardly. At its rear extremity the lever 56 is provided with an upwardly rearwardly inclined pin 112 which lies in the path of the roller 95. The forward end of the lever 56 is held downwardly, and consequently its rear end is held upwardly, resiliently, by means of a spring 113 secured to the lever 56 and to the bracket 20. As the player arm moves over the record, as a result of the engagement of the needle with the recording spiral thereof, the tooth 96 moves progressively over the serrated edge of the strip 111. When the player arm has reached a position inwardly of the record, beyond which no recording is present, the roller 95 engages the pin 112 and depresses the rear end of the lever 56 so as to elevate its forward end out of contact with the cam 57, causing the clutch elements to move into engagement, with the result that the shaft 43 is driven by the motor.

In certain types of record there is an eccentric groove into which the needle passes at the end of the playing of the record. In the case of such a record the reverse movement of the player arm and the similar movement of the arm 94 causes the pivoted tooth 96 to depress the rear end of the lever 56, with similar effect.

The lever 106, which is pivoted at an intermediate point on the shaft 104, carries at its forward end a roller 114 which rides on the upper edge of the player arm translating cam 44. At its rear end the lever 106 carries a roller 115 which is adapted to ride upon the helical cam 97. It will readily be understood that when the shaft 43 is rotated to rotate the cam 44 the forward end of the lever 106 is elevated and its rear end is depressed. The pressure applied by the rear roller 115 beyond the helical cam 97 causes the swinging frame, together with the player arm, to swing in counter-clockwise direction, as viewed in plan, against the action of the spring 99.

The lever 107 carries at its forward end a roller 116 which is adapted to ride on the player arm tilting cam 45. At its rear end the lever 107 is provided with an arcuate portion 117 normally located immediately below the roller 93, the element 117 being shaped so as to conform to the path of the roller 93, during the swinging movements of the player arm. When the forward end of the lever 107 is depressed by the cam 45, the arcuate portion 117 is correspondingly elevated and engages the roller 93 and elevates the rod 91. The elevation of the rod 91, through its contact with the roller 90, elevates the player arm 60 to a sufficient degree to remove the needle 33 from the record, as hereinbefore described. It will be understood that when the cam 45 permits the forward end of the lever 107 to rise again, under the action of a spring 118, the arcuate element 117 drops and the player arm moves downwardly somewhat so as to bring the needle into contact with the recording groove of the phonograph. The arcuate rear portion 117 of the lever 107 has secured thereto the upper end of the spring 103, which as hereinbefore described, is connected to the latch 102. When the arcuate element 117 is in its lowest position, there is no tension in the spring 103 and the latch 102 falls to its lowest position by its own weight. When, however, the arcuate element 117 is in its elevated posi-

tion there is sufficient tension on the spring 103 to raise the latch 102 sufficiently to lock the swinging frame to the bar 98 as hereinbefore described.

The lever 76, previously referred to, which effects the elevation of the player arm and associated carriages 65 and 72, by means of the link 75, extends forwardly of the machine and is pivoted adjacent its forward end, being there provided with a U bend so as to provide a pair of 10 bearings whereby it is pivotally mounted in one of the frame bars 16. The forward end of the returned portion of the lever 76 is connected by a link 118 to a bellows 119 provided with a conventional flap valve 120. It will readily be 15 seen with reference to Fig. 4 that when the player arm and associated parts are permitted to drop under their weight, the link 118 will tend to open the bellows 119. The bellows accordingly restrains the descent of the player arm 20 and associated parts so as to avoid injury to the sensitive elements comprised therein.

A spring 121 is connected to the frame 14 and to the lever 76 so as to take part of the weight of said lever. Another spring 122 extends from 25 the lever 76 upwardly to the upper end of a finger 123 which extends upwardly from an arm 124 pivotally mounted on the same frame bar 16 as is the lever 76. The arm 124 is provided with a returned end so as to comprise a U-shaped 30 pivoted end which is located on both sides of the U-shaped end of the lever 76. The lever 76 and the arm 124 are held against axial displacement by means of collars 125 mounted on the frame arm 16 which carries said lever and arm. 35 Adjacent its forward end the arm 124 is provided with a lug 126 which overhangs the lever 76. This lug carries a screw 127 adapted to make contact with the lever 76, the lever 76 being accordingly adjustable with respect to the 40 arm 124 by merely actuating the screw 127. On its outer side, the arm 124 carries a roller 128, which rides on the player arm and elevating cam 46.

It will readily be understood that when the cam 45 46 is rotated the arm 124 will be raised by the roller 128 and the spring 122 will move the lever 76 upwardly, this upward movement in turn effecting the elevation of the player arm and its carriages. As will hereinafter be described, the 50 upward movement of these elements is arrested at a predetermined position so that in most cases the movement of the lever 76 is terminated before that of the arm 124. The further upward movement of the arm 124 occurs with a corresponding 55 expansion of the spring 122. As soon as the cam 45 permits it, the arm 124 moves downwardly again until the screw 127 makes contact with the lever 76.

The record selecting mechanism which determines the position at which the player arm and its associated carriages stops will now be described. This mechanism comprises a vertical rod 129 pivotally mounted between the bridge members 18 and 19. This rod is provided with 60 radially projecting pins 130 equi-distantly spaced along the length of the rod, the spacing between the adjacent pins being substantially equal to the spacing between adjacent record discs and the similar spacing between adjacent openings 81 70 in the rod 71. The same number of pins 130 as records which the machine is intended to play, are provided and they are located upon the rod 129 in a helical series which goes around the rod once. Viewed in plan, as in Fig. 2, no two pins 75

130 are in superimposed relation, and they are spaced uniformly around the longitudinal axis of the rod 129. In the present case, where ten records are to be played, the angular displacement 5 between one pin 130 and the next is thirty-six degrees, and this displacement occurs downwardly along the rod 129 in a clockwise direction, as viewed in plan.

In the present embodiment of the invention 10 means are provided for rotating the rod 129 through the angular distance between adjacent pins so as to bring these pins consecutively into the path of the dog 77 on the carriage 72. In the present invention, the progressive rotation of the 15 rod 129 is effected in a counter-clockwise direction, as viewed in plan, with the result that the pins 130 are brought into cooperative relation with the dog 77 in downward order, and after the lowest pin has been brought into operative 20 relation with the dog 77 the uppermost pin is then brought into operative position, and so on.

A star wheel 131 is rigidly mounted on the rod 129 at a position below the horizontal partition 11. This star wheel has the same number of teeth 25 as there are pins 130. As best shown in Fig. 3, the teeth of the star wheel are relatively pointed, and the recesses between the teeth are of arcuate form so as to receive a roller 132 carried by an arm 133 mounted on the adjacent post 17. The 30 arm 133 is biased toward the star wheel 131 by means of a spring 134 connected to a pin carried by the arm 133 and to a screw 135 rigidly mounted on said post 17. Above the star wheel 131 and pivotally mounted on the rod 129 is an arm 136, which normally extends toward the right and is provided with a pad 137, which bears against the adjacent post 17. On its under side the arm 136 has pivotally mounted thereon a dog 138 which is directly inwardly and rearwardly adapted 40 to engage the teeth of the star wheel 131. The dog 138 is normally held in contact with the star wheel by means of a spring 139. The rearward end of a bar 140 is pivotally connected to the arm 136. The forward end of the bar 140 is pivotally 45 connected to an arm 141 pivotally mounted on the inner side of the right hand frame member 15. A stop 142 mounted on the frame member 15 limits the rearward movement of the arm 141.

Its forward movement is limited by the engagement of the stop 142 with the post 17, as heretofore described. The arm 141 is provided with a roller 143, which is adapted to be engaged by the arm 49, previously mentioned, which arm is mounted on the shaft 43, as hereinbefore described. During the revolution of this shaft the arm 49 comes into contact with the roller 143, and the arm 141 and bar 140 are moved rearwardly. This rearward movement causes the arm 136 to move rearwardly, and the dog 138 turns the star wheel 131 through a distance equal to the distance between the teeth. The consequent rotation of the star wheel 131 causes the roller 132 to rise out of its recess and pass into the next recess, thus holding the rod 129 in position to effect the playing of the next consecutive record, and in the case of the present embodiment of the invention, in the record next below that just played.

It will be seen that the movement of the star 70 wheel 131 through one tooth distance is effected automatically every time the shaft 43 rotates. This shaft rotates once between the playing of consecutive records, with the result that the selective mechanism will cause the playing of the records in downward sequence unless manual selec-

tion is interposed. The manner in which this may be done will now be described.

At its upper end the arm 141 is provided with an eye, which receives a rod 144, which is provided with a bearing 145 on the frame member 15 and projects outwardly through the front wall of the housing 10, as best shown in Fig. 3. The rod 144 is provided slightly forwardly of the arm 141 with a collar 146. Between the collar 146 and the arm 141 the rod 144 is provided with a coil spring 147. 10 This coil spring normally holds the rod 144 in a forward extreme position defined by the engagement of a collar 148 with the bearing 145.

Intermediate between the collars 146 and 148 the rod 144 is provided with a collar 149 rigidly mounted on said rod. A bellcrank lever 150 is mounted on the frame member 15 so that one end 151 is adapted to enter the path of the collar 149 when the rod 144 is moved rearwardly. The bellcrank lever 150 includes a downwardly extending 20 arm upon which a roller 152 is mounted. This roller rides upon the selector locking cam 47 and is adapted to be drawn toward said cam by means of a spring 153.

It will readily be seen, with reference to Fig. 5, 25 that when the roller 152 is riding along the low part of cam 47 the end 151 of the bellcrank lever 150 will be in a slightly higher position than shown in Fig. 5, so that inward movement of the rod 144 is effectively prevented until after the 30 roller 152 has moved to the corresponding rise of the cam 47 to a higher position thereon. This lock is for the purpose of preventing interference with the selector mechanism during the elevation of the player arm and associated parts until after 35 these parts have been locked in a desired elevated position by the engagement of the pin 80 in one of the openings 81. After this occurs, the selector mechanism is released and the next recording which the patron desires to be played can be selected. As previously indicated, the dog 77 is 40 pivotally mounted and spring held upon the carriage 72 so that it may move freely past a pin 130 located in its downward path.

In order that the patron may select the record 45 which he desires to play, I connect the rod 129 with an indicator 154, which is shown as a disc provided with bores corresponding to the number of records employed. This disc is mounted on a shaft 155 having a bearing carried by one 50 of the frame members 15. At its lower end the shaft 155 is provided with a tooth wheel 156, which is connected by an endless chain 157 to a similar tooth wheel 158 rigidly mounted on the rod 129. 55

I provide on the partition 11 a pin 159, which registers with the appropriate figure of the disc 154 so that the patron may know which record is to be played. Adjacent the disc 154 I place upon the partition 11 an index 160, which bears the 60 corresponding numbers and the titles of the records to which they relate. It will be immediately apparent that the patron can effect the rotation of the rod 129, one tooth at a time, by pressing the rod 144 inwardly, except at that time 65 during which the rod is locked. The rotation of the rod 129 is accompanied by a similar rotation of the disc 154. By the appropriate number of pushes on the rod 44, the patron can bring the rod 129 to position to play any desired selection 70 on the index 160.

The instrument described is particularly adapted for use as a coin freed machine, the insertion of a coin electrically controlling the operation 75 of the device and the supply of current to the

motor. The typical wiring diagram is superimposed upon Fig. 3. The reference numeral 161 designates a conventional coin insertion device, which projects the coin into a coin chute 162. In 5 passing through the coin chute the coin completes a circuit, including leads 163, which are electrically connected to a switch box 164 of known type. This switch box is adapted to complete a circuit between two leads 165 and 166. 10 It comprises a projecting lever 167 adapted to be engaged by the arm 48 at the end of each revolution of the shaft 43 so as to open the switch. The lead 165 is connected to one of the power leads. The lead 166 is connected to the motor 40 and 15 also to the amplifier diagrammatically illustrated at 172. The other power lead 168 is connected to the amplifier 172, to the motor 40, and to the switch box 164. Appropriate leads 169 extend from the amplifier to the pick-up 64 and appropriate leads 170 extend from the receiver to the 20 loud speaker 171, which may be mounted adjacent a suitable opening in the front wall of the cabinet 10.

If desired, the switch box 164 may be of the 25 general type described and claimed in the pending application, Serial No. 584,131, filed December 31, 1931, by Noel M. Seeburg. That is, it may be a counting or accumulating switch box so that a plurality of coins may be inserted at one 30 time, with the result that a corresponding number of records are played. In other words, the box contains mechanism so that if ten coins of appropriate value for the playing of a record are inserted, the leads 165 and 166 will be connected 35 by the switch box until the arm 48 strikes the lever 147 ten times.

The operation of the device will readily be understood from the foregoing description, in 40 which I have given both a description of the various mechanisms and the manner in which they operate. For the sake of greater clarity I now give a short résumé showing the manner in which the various functions and operations are interrelated.

45 The machine is normally stopped by the engagement of the arm 48 with the arm 161 of the switch box 164. This occurs immediately after the player arm 60 and its associated carriages have fallen to their lowermost position. The rod 144 is actuated a desired number of times to bring the appropriate pin 130 into alignment with the dog 77. The number of the pin is indicated by the pin 159 in relation to the numerals on the dial 154, and the title of the selection to be played 50 can be read by the patron on the index 160.

55 One or more coins of the appropriate denomination are inserted into the coin chute 162, which, through the leads 163, sets the switch box 164 for the playing of the corresponding number of records. The switch box 164 makes the circuits of the motor 40 and the amplifier 172 so that the motor immediately starts operating.

At this time the shaft 43 is clutched to the pinion 42 so that the shaft 43 is driven. The 60 roller 114 of the lever 106 is riding on the elevated portion of the cam 44 so that the player arm 60 is maintained deflected to the right of the records. The roller 116 is riding on an elevated portion of the cam 45 so that the rod 91 65 is in its highest position with respect to the main swinging frame composed of the rods 68 and 71 and the elements rigidly connecting them. The roller 128 is located on the lowest portion of the cam 46 so that the player arm and its associated 70 carriages are in their lowest position. The roller 75

152 is located on the highest portion of the cam 47 so that the selector control arm 144 is free from adjustment in the manner described.

The rotation of the shaft 43 and the cams and elements mounted thereon is in the clockwise direction as viewed from the left of the machine; that is, as shown in Figs. 4 and 5. As this rotation continues, the roller 152 moves down a fall on the cam 47, bringing the end 151 into the path of the collar 149 so as to prevent actuation of the selector rod 144. The roller 128 now rides up a rise on the cam 46, elevating the player arm 60 and associated carriages until the dog 77 makes contact with the appropriate pin 130. When this occurs, the upward movement of the player arm, 10 associated carriages, and the lever 76 is terminated, and further ride of the roller 128 upon the rise of the cam 46 results merely in a separation of the lever 76 and arm 124 in the manner hereinbefore described. After the roller 128 has 15 reached its highest position on the cam 46, along which it rides for some time, the roller 114 passes over a fall on the cam 44, which permits the elevation of the roller 115 and the consequent swinging of the bar 98 and the whole swinging elements 20 associated with the player arm in clockwise direction, as viewed in plan, until the arm 98 is arrested by contact with the screw 100.

25 During this swinging movement of the player arm, the sliding carriages which carry it become locked to the rod 71 by the entry of the pin 80 into the appropriate opening 81. This corresponds to the position of the needle 63, immediately above the initial recording spiral on the record.

30 Immediately after the bar 98 is arrested by the screw 100, the roller 128 passes over a fall on the cam 46, allowing the arm to return to engage the relation with the lever 76. Immediately after this occurs, the roller 116 passes over a fall on 35 the cam 45 so that the rear arcuate portion 117 of the lever 107 moves downwardly and permits the needle 63 to drop into contact with the recording spiral of the record, the player arm 60 being supported by the contact of the needle with 40 the record during the playing. As hereinbefore explained, the downward movement of the arcuate portion 117 is accompanied by a release of the latch 102 so that all the swinging elements other than the bar 98 are free to swing inwardly while 45 the record is being played. Immediately after this occurs, the arm 49 meets the roller 143 of the selector mechanism and rotates the star wheel 131 one tooth, bringing the next downward pin 130 into alignment with the dog 77. At the same 50 time the roller 152 rides up a rise on the cam 47 so that the selector actuating rod 144 is unlocked, permitting the patron to make any other 55 selection he desires, either while instrument is playing or standing still, until the rod 144 is again locked in the cycle of operation of the machine.

60 The forward end of the lever 56 now rides over the surface 58 of the cam 57 and displaces the collar 52 to the right, as viewed in Fig. 1, until 65 the pin 51 is withdrawn from the opening in the disc 50. When this occurs, the shaft 43 is promptly stopped by the brake 59.

65 During the swinging movement of the player arm into initial playing position, the pivoted 70 tooth 96 is brought into contact with the serrated strip 111 and remains in contact therewith as the player arm is carried over the recorded surface of the record. This results, in either of two ways, in the clutching of the shaft 43 to the pinion 42. 75

When the rotation of the shaft 43 is resumed the roller 116 passes over a fall on the cam 45 so that the rod 91 and consequently the player arm are elevated slightly. Continued rotation of the shaft 43 causes the roller 114 to ride up a rise on the cam 44. The consequent depression of the roller 115, which coacts with the helical cam 97, causes the player arm and associated parts to swing outwardly until the element 70 becomes locked to the bar 98 by means of the latch 102. Thereafter the bar 98 moves outwardly with the player arm and other swinging parts until the pin 80 is withdrawn from its opening 81, whereupon the player arm and its associated carriages fall in the manner hereinbefore described. After this the engagement of the roller 128 with the cam 46 provides a lower stop for the downward movement of these carriages.

The screw 121 may be adjusted to define the lowest position of the player arm, which is preferably such that substantially no elevation is necessary in order to bring the pin 80 into the lowest opening 81. That is, the lowest position of the player arm 60 is slightly above the lowermost record. The continued rotation of the shaft 43 brings the arm 48 into contact with the switch arm 167. If only one coin has been inserted, this contact effects the stoppage of the motor and it remains stopped until a further coin is inserted. If a plurality of coins had been inserted and the switch box 164 is of the counter or accumulator type referred to, then the contact of the arm 48 with the arm 167 merely affects the counting mechanism without stopping the motor, and the sequence of operations described above is repeated again and again until the phonograph has played as many records as coins were inserted.

Although the present invention has been described in connection with the specific details of a preferred embodiment thereof, it must be understood that such details are not intended to be limitative of the invention except in so far as set forth in the accompanying claims.

Having thus described my invention, what I claim as new and desire to secure by Letters Patent of the United States is:

1. A selective automatic phonograph comprising means for supporting in superposed spaced relationship a plurality of phonograph records, means for rotating said records, a player arm adapted selectively to cooperate with said records, mechanical means for raising said player arm past all said records, and selector means for arresting said player arm to determine the record to be played, said mechanical means being resilient to permit arrest of said arm in cooperative relation with any of said records.

2. A selective automatic phonograph comprising means for supporting in superposed spaced relationship a plurality of phonograph records, means for rotating said records, a player arm adapted selectively to cooperate with said records, automatic means adapted to raise and lower said arm past a plurality of records, selector means adapted to limit the raising of said arm to effect the playing of a certain record, and automatic means for actuating said selector means at the end of the playing of a record.

3. A selective automatic phonograph comprising means for supporting in superposed spaced relationship a plurality of phonograph records, means for rotating said records, a player arm adapted selectively to cooperate with said records, mechanical means adapted to raise and

lower said arm past a plurality of records, selector means adapted to limit the raising of said arm to effect the playing of a certain record, and manually operated means for actuating said selector means to effect the playing of a desired record, said mechanical means being resilient to permit arrest of said arm in cooperative relation with any of said records.

4. A selective automatic phonograph comprising a multiple turntable adapted to carry a series of superposed records in vertically spaced relation, a vertical frame adjacent said turntable, a carriage mounted and adapted to slide up and down thereon, power operated mechanism for elevating the carriage on the frame, selective means for limiting the upward sliding movement of the carriage, means actuated by said power operated mechanism for actuating said selective means, and manually operated means for actuating said selective means.

5. A selective automatic phonograph comprising a multiple turntable adapted to carry a series of superposed records in vertically spaced relation, a frame mounted to swing on a vertical axis, adjacent said turntable, a carriage slidably mounted on said frame, means for preventing said carriage from swinging, a carriage supported upon and slidable with the first said carriage and adapted to swing in horizontal planes with the frame, a player arm pivotally supported on the last said carriage to swing therewith, automatic means for raising the first said carriage to raise the player arm, and means carried by said vertical frame for tilting the player arm to raise and lower it from and to the record.

6. A selective automatic phonograph comprising a multiple turntable adapted to carry a series of superposed records in vertically spaced relation, a vertical frame adjacent said turntable, a player arm slidably mounted on said frame to be moved into various positions thereon, said player arm being adapted to swing slightly about a horizontal axis so as to enable it to drop on to a record and elevate therefrom, and a vertical bar extending along said frame, oblique parallel links pivotally secured to said frame and to said bar, and means for moving said bar longitudinally whereby said links cause it to engage the player arm at any of its positions to effect said swinging thereof.

7. A selective automatic phonograph comprising a multiple turntable adapted to carry a series of superposed records in vertically spaced relation, a vertical frame adjacent said turntable adapted to swing about a vertical axis, a carriage slidably mounted on said frame in the vertical direction so as to be movable into various positions thereon, means on said carriage engaging said frame to cause it to swing therewith, a player arm mounted on said carriage adapted to swing with said carriage and adapted to swing slightly about a horizontal axis so as to enable it to drop on to a record and elevate therefrom, a bar extending along said frame and adapted to be moved to effect said slight swinging of the player arm.

8. A selective automatic phonograph comprising a multiple turntable adapted to carry a series of superposed records in vertically spaced relation, a vertical frame adjacent said turntable adapted to swing about a vertical axis, a carriage slidably mounted on said frame to be moved into various positions thereon, a player arm carried by said carriage, means for swinging the frame to bring the player arm into cooperative

- relation to the record to be played, and means brought into operation by last said swinging for locking the carriage temporarily to said swinging frame.
5. 9. In a selective automatic phonograph, in combination, an elongated vertical frame adapted to swing about a vertical axis, a carriage slidably mounted thereon, means for preventing swinging of the carriage with the frame, means for 10 raising said carriage, a second carriage slidably with the first said carriage, means on the last said carriage engaging the swinging frame so as to cause said carriage to swing therewith, a player arm mounted on the last said carriage, and 15 a latch actuated by relative movement between the two carriages adapted to lock the second said carriage temporarily to the swinging frame.
10. In a selective automatic phonograph, in combination, an elongated vertical frame adapted 20 to swing about a vertical axis, a carriage slidably mounted thereon, means for preventing swinging of the carriage with the frame, resilient means for raising said carriage, selector means comprising a plurality of spaced elements adapted 25 selectively to be brought into the path of said carriage to stop its upward movement at a predetermined position, a second carriage slidably with the first said carriage and adapted to swing with the swinging frame, and a player arm mounted on the last said carriage.
30. 11. In a selective automatic phonograph, in combination, an elongated vertical frame adapted to swing about a vertical axis, a carriage slidably mounted thereon, means for preventing
- swinging of the carriage with the frame, resilient means for raising said carriage, selector means comprising a plurality of spaced elements adapted selectively to be brought into the path of said carriage to stop its upward movement at a predetermined position, a second carriage slidably with the first said carriage, means on the last said carriage engaging the swinging frame so as to cause said carriage to swing therewith, a player arm mounted on the last said carriage, and a latch actuated by relative movement between the two carriages adapted to lock the second said carriage temporarily to the swinging frame. 5
12. In a selective automatic phonograph, in combination, an elongated vertical frame adapted 15 to swing about a vertical axis, a carriage slidably mounted thereon and adapted to swing therewith, means for raising said carriage, a player arm mounted on the carriage, and a latch actuated by the swinging movement of the carriage 20 for locking the carriage temporarily to the swinging frame.
13. In a selective automatic phonograph adapted to receive a series of superposed spaced records, in combination, a player arm, a carriage 25 therefor adapted to slide to bring the tone arm into cooperative relation with any of the records, a selector rod provided with a series of projecting elements located out of axial alignment, and means for rotating the rod to bring one of said elements into the path of said carriage to arrest it adjacent a predetermined record. 30

RUSSELL I. WILCOX.
